United States Patent Office.

JOHN U. NEF, OF HOUSATONIC, MASSACHUSETTS.

Design No. 4,955, dated May 30, 1871.

DESIGN FOR A BED-QUILT.

The Schedule referred to in these Letters Patent and making part of the same.

To all whom it may concern:

Be it known that I, JOHN U. NEF, of Housatonic, in the county of Berkshire and State of Massachusetts, have invented a new and original Design for a Bed-Quilt; and I do hereby declare that the following is a full, clear, and exact description thereof, which will enable others skilled in the art to make and use the same, reference being had to the accompanying drawing forming part of this specification, which represents an outline of my new design for a bed-quilt.

This invention relates to two new features of design for a bed-quilt, one being the design for the border, and the other for the main portion or body of the quilt.

The border A is composed of three parallel strips or sections, *a*, *b*, and *c*, the middle section *b* being of

considerable width, and containing the compound-cross design *d* shown.

At each corner of the quilt the border forms the corner design *e*.

The body B of the quilt is composed of peculiar-shaped stars, *f*, and of compound squares *g*, formed between the united arms of four adjoining stars.

These designs are woven into the fabric, preferably in the same color of which the ground is made.

I claim as my invention—

1. The design for the border of a quilt, as shown.
2. The design for the main part or body of a quilt, as shown.
